THREAD BOBBIN AND METHOD OF MAKING

Emil B. Nelson, East Hampton, Conn., assignor
to The Lloyd E. Cone Thread Co., Moodus,
Conn., a corporation of Connecticut

Application April 5, 1946, Serial No. 659,927

7 Claims. (Cl. 112—251)

1

The invention relates to a bobbin of the type comprising a cylindrical mass of thread wound on a tubular core and supported at its ends by means of discs which are suitably secured to the end portions of the core. A wide variety of bobbins of this general type have been heretofore proposed and used and there are many different means for securing the end discs to the core. In most prior instances the end portions of the core tube have been spun or swaged outwardly to form distinct beads or flanges which project beyond the inner edges of the discs to lock the said discs in place.

The general object of the present invention is to provide a bobbin of the type described and a method of making the bobbin wherein the discs are held in place by the mere radial expansion of the end portions of the core tube so as to forcibly engage the said end portions with discs, without forming any definite bead or flange at the ends of the tube.

A more specific object of the invention is to provide a bobbin and a method of making the same wherein the tube is formed of a relatively soft material, and wherein the discs are formed of a material which is relatively much harder so that the relatively hard discs will resist the expansion of the tube at the zones of engagement therewith, the tube being expanded at both sides of each zone of engagement so that the discs are seated in self-formed grooves in the tube and are thus firmly held in place.

Other objects of the invention will be apparent from the drawing and from the following specification and claims.

In the drawing I have shown in detail a preferred form of bobbin embodying the invention and a preferred method of making the bobbin, but it will be understood that various changes may be made in the bobbin and the method as shown, and that the drawing is not to be construed as defining or limiting the scope of the invention, the claims forming a part of this specification being relied upon for that purpose.

Of the drawing,

Fig. 1 is a longitudinal sectional view showing a bobbin at the completion of the initial step of the method.

Fig. 2 is a sectional view showing the bobbin at the completion of the second step of the method.

Fig. 3 is a sectional view showing the bobbin at the completion of the third step of the method.

Fig. 4 is a sectional view showing the completed bobbin.

Fig. 5 is an end view of the completed bobbin.

2

Fig. 6 is a combined sectional and elevational view showing an apparatus by means of which the second step of the method may be practiced.

Fig. 7 is a combined sectional and elevational view showing an apparatus by means of which the final step of the method may be practiced.

Referring to the drawing, particularly Fig. 1 thereof, 10 is a tubular core which may be formed of any suitable material, but which is preferably formed of a relatively soft material such as paper or compressed fiber. Thread is cross-wound on the core 10 in any usual or preferred manner to form a centrally apertured cylindrical thread mass 12. The length of the thread mass and the length of the core are preferably substantially the same, but the thread mass may be slightly shorter than the core as shown.

After the thread mass 12 has been formed it is compressed by pressure applied longitudinally so that its length is substantially reduced, as shown in Fig. 2. Preferably, when pressure is applied to the thread mass 12 to reduce the length thereof, pressure is also simultaneously applied to the ends of the tube 10 to somewhat reduce the length thereof. The endwise compression of the tube 10 causes the walls thereof to be slightly increased in thickness, the inner diameter remaining substantially the same. Due to the compression the interior and exterior surfaces of the tube 30 may become somewhat irregular, as indicated in Fig. 2, but the interior diameter remains substantially uniform throughout. The tube 10 is compressed to a much smaller extent than the thread mass 12, the result being that the end portions 14, 14 thereof protrude, as indicated in Fig. 2.

After the thread mass has been compressed, as shown in Fig. 2, two thin centrally apertured discs 16, 16 are assembled with the compressed thread mass 12 and with the protruding end portions 14, 14 of the tube, as shown in Fig. 3. The apertures in the discs 16, 16 are of such diameter that the inner edges of the discs closely fit the outer surface of the protruding end portions. The discs 16, 16 are of substantially uniform thickness throughout and they are preferably formed of a material much harder than that of the tube 10 and the discs may advantageously be formed of a transparent plastic material which enables the thread mass to be conveniently viewed at the ends. This makes it possible to conveniently observe the color of the thread and also to observe the amount of thread remaining on the bobbin. The discs 16, 16 are preferably very thin, the thickness thereof being substantially exaggerated in the drawing. Each disc 16 may have

a flat central portion 18 which is perpendicular to the axis thereof. Each disc 16 also comprises a portion 20 which is outwardly curved in transverse section. The diameter of the end discs 16, 16 is slightly greater than that of the thread mass, and the inner faces of the discs engage near their periphery with the peripheral corners of the thread mass, as shown.

After the parts have been assembled, as shown in Fig. 3, longitudinal pressure is applied to the ends of the tube 10, this pressure serving to further shorten and expand the tube. The walls of the tube are further thickened but the internal diameter remains substantially the same. Due to the fact that the central portion of the tube is surrounded by the compressed thread mass, the said inner portion is expanded to only a very slight extent, if any, but the protruding end portions 14, 14 are substantially expanded and shortened, as shown in Fig. 4. The expansion of the end portions 14, 14 causes them to firmly grip the discs 16, 16 to hold the discs in place. No substantial distortions or changes in shape occur in the discs 16, 16 during the expansion of the tube. Furthermore, in view of the fact that the material of the tube is relatively soft, whereas the material of the discs is relatively hard, the tube can have little or no expansion at its zones of contact with the discs, but it expands at both sides of the said zones of contact, the result being that after expansion the inner edge portions of the discs are seated in self-formed annular grooves near the outer ends of the expanded end portions 14, 14.

It will be seen from the foregoing description that the discs 16, 16 are firmly secured to the tube without the formation of any distinct beads or flanges on the tube, and that the discs themselves are not in any way bent or deformed. With the discs seated in self-formed grooves, as shown and described, they are firmly held even when the bobbin is nearly empty and when they are no longer supported by the thread mass. The grooves not only prevent outward movement of the discs but they also prevent inward movement thereof. Not only are the discs held in place by their engagement in the grooves, but also they are subjected to radially outward pressure which would tend to hold them in place frictionally, even if there were no grooves.

It will be observed that in the completed bobbin, as shown in Fig. 4, the curved portions 20, 20 of the discs are tangent to planes which are spaced outwardly from the ends of the tube, thus making it impossible for thread looped around the bobbin to be caught by the protruding portions of the tube.

Fig. 6 shows an apparatus which may be used for compressing the thread mass and the tube from the condition as shown in Fig. 1 to the condition as shown in Fig. 2. As shown, the apparatus comprises an anvil 22 supported in a base 24. The anvil has a central hole 26, the diameter of which is substantially the same as the diameter of the hole in the tube 10, and the said hole is countersunk, as shown at 28, to receive one end portion 14 of the tube. A plunger 30 is positioned vertically above the anvil 22 and is guided for vertical movement in a bearing member 32 suitably supported on the base 24 by means of uprights 34, 34. The plunger 30 is centrally apertured to receive a vertically movable pilot rod 36 and the aperture in the plunger is provided with a countersink 38 to receive the other end portion 14 of the tube. The upper end of the

pilot rod 36 is secured to a member 40 which is vertically reciprocable by suitable means not shown. A coil spring 42 surrounds the plunger 30 and tends to hold it in its upper position. Upward and downward movement is limited by means of a screw 44 which enters a slot in the plunger.

In operation the assembly comprising the tube 10 and the thread mass 12, as shown in Fig. 1, is placed on the anvil 22, as shown by dotted lines, and then the member 40 is moved downward. The downward movement of the member 40 first causes the pilot rod 36 to move into and through the tube 10 to support the inner wall of the tube and prevent collapsing. Continued downward movement of the member 40 causes it to engage the top of the plunger 30 thus forcing the plunger downward into engagement with the thread mass which is compressed longitudinally to the condition shown in Fig. 2. The depths of the two countersinks 28 and 38 are preferably such that the ends of the tube 10 are engaged just prior to the completion of the compression of the thread mass so that the tube is compressed and somewhat shortened as shown in Fig. 2.

The apparatus shown in Fig. 7 is very similar to that shown in Fig. 6, the only difference being that a different anvil 46 is substituted for the anvil 22 and a different plunger 48 is substituted for the plunger 30. The top face of the anvil 46 and the bottom face of the plunger 48 are shaped to conform to the shapes of the discs 16, 16, and the said anvil and the said plunger are formed with very shallow countersinks 50 and 52 to receive the end portions 14, 14 of the tube.

The assembly shown in Fig. 3 is placed on the anvil 46, as shown by dotted lines in Fig. 7, and the operation as described in connection with Fig. 6 is repeated. The pilot rod 36 first moves into and through the tube to support the inner wall thereof and prevent collapsing, and continued downward movement of the member 40 causes the plunger 48 to move downward to engage the assembly. The horizontal faces of the countersinks 50 and 52 engage the ends of the tube 10 causing the end portions 14, 14 thereof to expand and grip the discs 16, 16, as already described in detail in connection with Fig. 4.

It will be understood that Figs. 6 and 7 are intended merely to illustrate simple means for practicing the method of the invention, and that in actual practice more elaborate and complete apparatus would be used. Such complete apparatus would include automatic means for feeding the bobbins from station to station, automatic means for applying the discs thereto, and automatic means for operating the pilot rods and plungers.

What I claim is:

1. In a wound thread bobbin, the combination of a central cylindrical tube of relatively soft material, a cylindrical mass of thread wound upon and supported by the tube and longitudinally compressed with portions of the tube adjacent the ends thereof protruding beyond the said compressed mass, and two centrally apertured thin circular discs of relatively hard material engaging the ends of the thread mass, the said discs having their inner portions substantially perpendicular to the axis of the tube and having their inner edges in engagement with the protruding portions of the tube, each end portion of the relatively soft tube being radially expanded except where expansion is resisted by the corresponding relatively hard disc so as to form a

continuous annular groove in which the inner edge of the disc is seated with the sides of the groove engaging the inner and outer faces of the disc.

2. In a wound thread bobbin, the combination of a central cylindrical tube of relatively soft material, a cylindrical mass of thread wound upon and supported by the tube and longitudinally compressed with portions of the tube adjacent the ends thereof protruding beyond the said compressed mass, and two centrally apertured thin circular discs of relatively hard material engaging the ends of the thread mass with their inner edges engaging the protruding portions of the tube, each disc having its extreme inner portion substantially perpendicular to the axis of the tube and spaced inwardly from the corresponding end of the tube and each disc being outwardly curved in transverse section so that a plane tangent to the outermost curvature is spaced outwardly from the corresponding end of the tube, each end portion of the relatively soft tube adjacent the corresponding relatively hard disc being radially expanded except where expansion is resisted by the disc so as to form a continuous annular groove in which the inner edge of the disc is seated with the sides of the groove engaging the inner and outer faces of the perpendicular portion of the disc.

3. The method of making a thread bobbin, which comprises in combination, winding a mass of thread on a tube of relatively soft material having a length substantially the same as that of the mass, compressing the thread mass longitudinally so as to leave the end portions of the tube protruding, assembling with the compressed thread mass and with the protruding end portions of the tube two thin discs of relatively hard material which closely fit the said end portions, and applying longitudinal pressure to the tube to shorten it and to cause the said end portions of the soft tube to expand at both sides of each hard disc so as to form annular grooves in which the discs are seated.

4. The method of making a thread bobbin, which comprises in combination, winding a mass of thread on a tube of relatively soft material having a length substantially the same as that of the mass, compressing the thread mass longitudinally so as to leave the end portions of the tube protruding, assembling with the compressed thread mass and with the protruding end portions of the tube two thin discs of relatively hard material which closely fit the said end portions, and applying longitudinal pressure to the tube to shorten it and to cause the said end portions of the soft tube to expand to a greater extent than the central portion, the expansion of the said end portions taking place at both sides of each hard disc so as to form annular grooves in which the discs are seated.

5. The method of making a thread bobbin, which comprises in combination, winding a mass of thread on a tube having a length substantially the same as that of the mass, compressing the

thread mass longitudinally and simultaneously applying longitudinal pressure to the tube to initially shorten it to an extent less than the extent of compression of the thread mass so as to leave the end portions of the tube protruding, assembling with the compressed thread mass and with the protruding end portions of the shortened tube two thin discs which closely fit the said end portions, and again applying longitudinal pressure to the tube to further shorten it and to expand the end portions thereof so as to cause the said end portions to grip the discs and hold them in place.

6. The method of making a thread bobbin, which comprises in combination, winding a mass of thread on a tube of relatively soft material having a length substantially the same as that of the mass, compressing the thread mass longitudinally and simultaneously applying longitudinal pressure to the tube to initially shorten it to an extent less than the extent of compression of the thread mass so as to leave the end portions of the tube protruding, assembling with the compressed thread mass and with the protruding end portions of the shortened tube two thin discs of relatively hard material which closely fit the said end portions, and again applying longitudinal pressure to the tube to further shorten it and to expand the end portions thereof so as to cause the said end portions of the soft tube to grip the hard discs and hold them in place.

7. The method of making a thread bobbin, which comprises in combination, winding a mass of thread on a tube of relatively soft material having a length substantially the same as that of the mass, compressing the thread mass longitudinally and simultaneously applying longitudinal pressure to the tube to initially shorten it to an extent less than the extent of compression of the thread mass so as to leave the end portions of the tube protruding, assembling with the compressed thread mass and with the protruding end portions of the shortened tube two thin discs of relatively hard material which closely fit the said end portions, and again applying longitudinal pressure to the tube to further shorten it and to expand the end portions thereof so as to cause the said end portions of the soft tube to expand at both sides of each hard disc so as to form annular grooves in which the discs are seated.
